Attorney

UNITED STATES PATENT OFFICE.

BERYL W. CAMPBELL, OF UTICA, OHIO.

CLOCK.

Application filed April 24, 1926. Serial No. 104,479.

My present invention has to do with 14 being provided upon its periphery with clocks; and its object is the provision of a hour numerals arranged in regular sequence, simple, durable and reliable clock embodying rotary disks instead of hands and located to be displayed in succession through the be- 60 signed to be used to advantage in automobiles.

Other objects and practical advantages of 10 the invention will be fully understood from the following description and claim when the 65 same are read in connection with the drawings, accompanying and forming part of this specification, in which:—

Figure 1 is a front elevation of the clock 15 constituting the preferred embodiment of my invention.

Figure 2 is a front elevation of the clock as the same appears when the face plate shown in Figure 1 is removed.

Figure 3 is a vertical central section of 20 the structure shown in Figure 2.

Figure 4 is a rear elevation of the said structure.

Figure 5 is a top plan view of said structure with a portion in horizontal section, the 25 sectional part being taken in the plane indicated by the line 5—5 of Figure 2.

Figure 6 is a horizontal section taken in the plane indicated by the line 6—6 of Figure 2.

30 Similar numerals of reference designate corresponding parts in all of the views of the drawings.

The face plate 1 shown in Figure 1 forms part of a casing in which the structure shown 35 in Figures 2 to 6 is disposed, and it will be noted from Figure 1 that the said face plate 1 is provided with sight openings 2 and 3 disposed one above the other in spaced relation.

40 The structure shown in Figures 2 to 6 is secured in any appropriate manner in the casing alluded to, and among other elements the said structure includes a frame 4 on the forward side of which are brackets 5, 6, 7 and 8, arranged one above the other in spaced relation, Figures 2 and 3. It will also be noticed that the upper bracket 8 is surmounted by an upright 9 and that the said upright 9 is equipped at its forward side 45 with a pendent resilient detent 10. This detent 10 is for cooperation with a wheel or disk 11 having rounded teeth 12, Figure 5. The said disk 11 is fixed to an upright shaft 13 journaled in the brackets 7 and 8, and 50 fixed to the said shaft 13 is the hour wheel 14 of my improvement, the said hour wheel

Manifestly the detent 10 in cooperation with the toothed disk 11 will preclude too free turning of the wheel 14 and will assure the said wheel 14 resting at all times with 65 one of its numerals in registration with the sight opening 2.

Fixed to the shaft 13 and disposed below the wheel 14 is a ratchet disk 16, and arranged to engage the said disk 16 is a dog 70 17 carried by a spring arm 18, as best shown in Figure 6. The spring arm 18 is connected at 19 to a reciprocatory member 20, guided at 21 on the frame 4, and it will be noted by particular reference to Figure 4 that the said 75 reciprocatory member 20 is connected to one arm 22 of a bell crank that is fulcrumed at 23 and is provided with a comparatively long arm 24 that is subject to the action of a retractile spring 25 and is equipped with 80 a lateral projection 26. When the free end of the arm 24 of the bell crank is raised, the dog 17 will be moved toward the left in Figures 2 and 6 so as to take a fresh hold on the ratchet disk 16, and when the free end 85 of said arm 24 is suddenly released and is pulled down by the contraction of the spring 25, the member 20, the spring 18 and the dog 17 will be moved toward the right in Figures 2 and 6 so as to turn the ratchet disk 90 16 the distance of one tooth and thereby present a succeeding number in registration or coincidence with the sight opening 2.

The free end of the arm 24 is raised for the purpose indicated through the medium 95 of a cam 27, preferably shaped as shown in Figure 4, the said cam 27 being fixed or otherwise appropriately mounted on what I term the hour shaft 28 of my improvement, and which hour shaft is designed to be rotated by any conventional or other appropriate clock mechanism which I have deemed it unnecessary to illustrate. I would also have it here understood that when desired the shaft 28 may be equipped with a finger 100 piece, not shown, and may be utilized as a setting post for the proper turning of the wheel 14 as well as the minute wheel designated by 29. At its forward end the shaft or post 28 is provided with a miter gear 30, Figures 2 and 3, and the said gear 30 is 105 arranged in mesh with a similar gear 31.

fixed to a shaft 32 journaled in the brackets 5 and 6, and which shaft 32 is appropriately fixed to the minute wheel 29, as appears in Figure 3.

5 The wheel 29 is provided on its periphery with numerals designated by 33 and arranged in regular sequence and designed to indicate minutes. I would also have it understood that the numbers 33 are designed 10 to be displayed in succession through the sight opening 3, Figure 1.

It will be apparent from the foregoing 15 that the cam 27 is caused to turn a complete revolution every hour, and that, therefore, at the completion of an hour, the wheel 14 will be turned through the proper part of a revolution so as to present a fresh numeral 15 opposite the sight opening 2 to indicate the new hour.

20 The winding shaft of the clock mechanism alluded to is designated by 50 and shown in Figure 2.

Manifestly my novel wheel clock is extremely simple and inexpensive notwithstanding the fact that it is reliable in operation; and it will also be appreciated that the novel clock is not liable to be effected by vibration ordinarily present in automobiles, and is not likely to be deranged by shocks 30 and jars.

I have entered into a detailed description of the structure constituting the preferred embodiment of my invention in order to impart an exact understanding of the said embodiment. I do not desire, however, to be understood as limiting myself to the structure shown and described, my invention being defined by my appended claim within the scope of which modifications may be made without departure from my invention. 40

Having described my invention, what I claim and desire to secure by Letters-Patent, is:—

In a clock and in combination, a minute wheel, an hour wheel, and means operable by 45 means for rotating the minute wheel for rotating or turning the hour wheel step by step; the said means comprising a cam, a ratchet disk fixed to the hour wheel, a reciprocatory member, a spring arm on said 50 member and carrying a dog in engagement with the ratchet disk, a bell crank having an arm connected to said reciprocatory member and also having an arm with a portion opposed to said cam, and spring means for holding said arm portion in contact with the cam.

55 In testimony whereof I affix my signature.

BERYL W. CAMPBELL.
